UNITED STATES PATENT OFFICE.

WILFRED B. MATHEWSON, OF NORTH WEYMOUTH, MASSACHUSETTS.

NEEDLE FOR TUFTING MACHINES.

Application filed June 1, 1920. Serial No. 385,396.

To all whom it may concern:

Be it known that I, WILFRED B. MATHEWSON, a citizen of the United States, residing at North Weymouth, county of Norfolk, 5 State of Massachusetts, have invented an Improvement in Needles for Tufting Machines, of which the following description, in connection with the accompanying drawing, is a specification, like characters on the 10 drawing representing like parts.

This invention relates to needles such as are used in machines for sewing and it has for its object to provide an improved needle which is constructed so that the operation 15 of threading it is greatly facilitated.

My improved needle is adapted for use in various kinds of machines where it is necessary to perform a sewing operation, but it is particularly applicable to needles that are 20 provided with a central thread-receiving bore leading to the eye and through which the thread is passed. As illustrative of one machine employing a needle of this type, I would refer to a tufting machine for tufting 25 mattresses and the like, but I wish it distinctly understood that the invention is not limited to a needle for a tufting machine, but may be embodied in needles employed in various other types of sewing machines. 30 In order to give an understanding of the invention, I have chosen in the drawings to illustrate it as it would be employed in a needle for a tufting machine.

Fig. 1 is a sectional view of a portion of a 35 tufting machine showing the manner in which the needle is mounted;

Fig. 2 is a longitudinal sectional view through the needle on the line 2—2, Fig. 3, said figure showing the manner in which the 40 needle is threaded;

Fig. 3 is a side elevation of the needle;

Fig. 4 is an enlarged section on the line 4—4, Fig. 2.

Inasmuch as the invention relates entirely 45 to the needle I have not thought it necessary to illustrate herein a complete tufting machine, but have only shown a sufficient portion thereof to enable the invention to be understood.

In Fig. 1 of the drawings, 1 indicates a portion of a mattress to be tufted, 2 represents the lower compressor or support on which the mattress rests, and 3 represents the upper compressor which is vertically 50 movable in the head portion 4 of the frame and which by its downward movement co-

operates with the lower compressor 2 to compress the mattress at the point where the tuft is to be inserted.

In tufting the mattress, the tufts which 60 are indicated at 5 are tied in place by means of tufting twine 6, the latter being manipulated by a tufting needle 7 which is carried in a vertically-movable needle-bar 8 and is adapted to penetrate the mattress 1, and also 65 by a suitable knotting mechanism (not shown) associated with the lower compressor 2 and which serves to form suitable knots in and to fasten the tufting twine 6 as it is inserted through the mattress. 70

For a more complete description of the construction and operation of the tufting machine as a whole, reference may be had to United States Patent No. 819,954, dated May 8, 1906. 75

The present invention relates simply to the needle 7, and as stated above, it has for its principal object to provide a novel construction of needle by which the operation of threading the needle is greatly facilitated. 80

The tufting needle which is usually employed is an eye-pointed needle, that is, it has an eye 9 adjacent the point 80 thereof. It is also provided with a central twine-receiving bore 10 through which the twine is 85 delivered to the eye 9.

The upper end 11 of the needle is inserted into a recess in the needle bar 8 and is shown as retained in place by suitable set screws 12. 90

Heretofore it has been the common practice to make these needles with a closed twine-receiving bore extending longitudinally of the needle, and the operation of threading the needle has involved inserting one end of the twine into the bore at the upper end of the needle and forcing the twine down through the bore to the eye. If the twine is of a soft nature this is a rather difficult and tedious operation, because the lack of stiffness in the twine permits it to bunch up and clog the bore. In order to prevent this and to facilitate the threading operation, I form my improved needle with a slot 95 extending longitudinally thereof which communicates throughout its length with the bore 10, but which is narrower than the normal diameter of the twine 6. Said slot is preferably constructed so that each side of the slot at the mouth thereof presents relatively sharp edges that are directed toward each other. The upper end of the slot is of 100 a width to freely admit the twine and from

105

110

this wide upper end the slot has a progressively-decreasing width to that of the body of the slot. In threading up the needle it is simply necessary to enter the twine into the upper end of the bore and draw it into the upper end of the slot, after which a pull on the twine in the direction of the point of the needle will draw it longitudinally of the slot and into the bore throughout the entire length thereof.

The needle herein shown has at its upper end a transverse opening 13 which communicates with the bore 10, and from this opening to the eye 9, the needle is provided with the slot 14 which communicates with the bore but which is narrower than the diameter of the twine 6. The slot is formed to present the relatively sharp edges 15 at the mouth thereof which are directed towards each other. The upper end 16 of the slot opposite the transverse aperture 13 is of a width to freely receive the twine 6, and at the lower end opposite the eye 9 the slot is also of a similar width, as shown at 17. In threading the needle, the twine 6 is inserted through the aperture 13 from the non-slotted side of the needle to the slotted side, so that the end of the twine projects through the aperture on the slotted side, as shown at 18 in dotted lines. This end of the twine is then drawn downwardly toward the point of the needle thereby drawing the twine into the slot 14, as indicated in full lines, Fig. 2.

Owing to the fact that the slot is of less width than the diameter of the twine 6 and is provided with the relatively sharp edges 15 which are directed towards each other, said edges will bite into the twine 6 as the latter enters the slot, as shown in Fig. 4, thus making it difficult to pull the twine transversely through the slot. Hence any pulling on the twine in the general direction of the arrow *a* in Fig. 2 will simply draw the twine down the slot 14, thus drawing it into the bore 10. When the twine has been drawn clear to the enlarged portion 17 of the slot, said twine will be occupying the bore throughout its entire length. The threading of the needle is then completed by inserting the end of the twine through the eye 9, as indicated in dotted lines Fig. 2. Owing to the fact that the slot is of less width than the diameter of the twine, there is no danger that the needle will become de-threaded by the twine working out through the slot 14 while the machine is in use.

By reason of this construction, therefore, the threading of the needle involves merely the three steps of inserting the twine through the aperture 13, pulling the twine downwardly longitudinally of the slot and then inserting the end of the twine through the eye 9.

The length of the needle is immaterial because with my invention a long needle can

be threaded with just as much facility as a short needle.

The needle is preferably inserted into the needle-bar so that the slot is situated on the front side of the needle. In the construction herein shown the needle bar is jointed, it having the main section 19 to which is pivotally mounted the section 8 to which the needle is secured. The twine passes from the source of supply longitudinally of the needle-bar section 19 and under a suitable tension 20 and thence through a diagonal aperture 21 formed in the needle bar section 8, thence along the back side of said needle bar section 8 to the aperture 13, and through the aperture 13 into the bore of the needle, and thence to the eye 9 thereof. The provision of the pivotally-mounted needle bar section 8 is of advantage because it facilitates the threading of the needle in the machine. If the twine breaks it is simply necessary to swing the needle bar section 8 upwardly, as shown by dotted lines, thereby placing the needle in such position that the operator can readily insert the twine through the aperture 13 from the back side of the needle, then pull the twine longitudinally of the needle to draw it into the bore, and then insert the twine through the eye 9. The needle-bar section 8 is held in its operative position by means of a spring-pressed retaining member 22.

In the above description I have referred to the thread which the needle controls as tufting twine because in the art of tufting mattresses such thread is usually referred to as twine. The character of the thread, however, is not important so far as the invention is concerned. As stated above, the invention is also applicable to needles which are to be used with sewing machines other than tufting machines, and, therefore, I do not wish to be limited to a tufting machine in the use of the invention. In other sewing machine adapted for uses other than tufting mattresses, the thread which is used may not be in the nature of twine, but will be thread of some other character.

I claim:

A needle for sewing machines comprising a pointed body provided at its pointed end with an eye and having a central thread-receiving bore leading to but terminating at the eye, said body also having a slot extending longitudinally thereof and throughout the length of the bore said slot communicating with the bore and having a progressively decreasing width from the bore to the periphery of the body, the body being shaped to present relatively sharp edges at the mouth of the slot which are directed toward each other.

In testimony whereof, I have signed my name to this specification.

WILFRED B. MATHEWSON.
